UNITED STATES PATENT OFFICE.

ALBERT D. GROVER, OF MALDEN, AND EARL E. BARBER, OF BOSTON, MASSACHUSETTS,
ASSIGNORS, BY MESNE ASSIGNMENTS, TO AUTOSALES CORPORATION, A CORPORA-
TION OF NEW YORK.

VENDING-MACHINE.

1,300,259.

Specification of Letters Patent. Patented Apr. 15, 1919.

Application filed December 15, 1911. Serial No. 666,006.

To all whom it may concern:

Be it known that we, ALBERT D. GROVER and EARL E. BARBER, citizens of the United States, and residing, respectively, at Malden, 5 county of Middlesex, State of Massachusetts, and Boston, county of Suffolk, State of Massachusetts, have invented certain new and useful Improvements in Vending-Machines, of which the following is a specifica- 10

tion. Our invention relates to vending machines adapted to be operated upon the deposition of a coin for the delivery of a suitable commodity, and has for its general object the 15 provision of a machine which is particularly adapted to deliver flat articles—such as envelopes, foldable drinking cups and the like. The flat articles (which for the sake of illustration will hereinafter be referred to as 20 drinking-cups) are arranged in a vertical stack in the magazine of the machine, so that a large number can be accommodated in a comparatively small space. This gives a machine of maximum capacity with mini- 25 mum dimensions. A machine of our construction, less than twelve inches high, can be charged with several hundred drinking cups. Our machine is thus well adapted for use in places where but little space is available—as, for instance, in the washrooms on 30 Pullman cars.

One object of our invention is to provide a vending machine having a slideable ejector movable over the bottom of the magazine 35 and adapted to engage the lowermost cup or envelop at the edge of its underside and thereby draw the same out of the magazine through the delivery-opening of the machine. The free or open end of the upper 40 side of the cup projects beyond the free edge of the underside, whereby the ejector causes the cup to gap at its open end when it engages the under edge thereof. In this way the ejector gets a good hold on the cup and 45 there is no danger of the ejector slipping out of engagement with the cup during the ejecting movement.

A further object of our invention consists in providing adjustable means at the bottom 50 of the magazine for normally supporting the forward end of the lowermost article above the delivery opening, the arrangement being such that the operation of the ejector causes automatic lowering of said support- 55 ing means to bring the forward end of the

lowermost article into alignment with the delivery opening. By means of this adjustable support the fraudulent withdrawal of articles from the magazine by means of a sharp instrument—such as a knife, a piece of 60 pointed wire, etc.,—is positively prevented. At the same time the automatic adjustment of the support when the ejector is operated, permits the ready delivery of the articles through the delivery opening by the ejector. 65 The idea of this adjustable support may be mechanically carried out in a number of ways, and we do not wish to be limited to the precise form shown for the sake of illustration in the accompanying drawings. 70

A further object of our invention is to provide a weight adapted to rest loosely on the stack of vendable articles for exerting a downward pressure at the forward end of the same, so as to insure the alignment of the 75 lowermost article at its forward end with the delivery opening in the machine. This weight also cooperates with the ejector to prevent operation of the latter when the machine is empty.

A further object of our invention is to provide operating connections between the ejector and a hand-operated member projecting outside of the casing, whereby a short movement of the hand-operated member causes an increased or multiplied movement of the ejector.

A further object of our invention is to provide a vending machine in which the operating parts are supported by a main casting. To the upper end of this casting is secured the magazine containing the articles, while from the lower portion thereof is removably suspended a coin receptacle which 90 performs the double function of receiving the deposited coins and inclosing the operative parts arranged below the main casting. 95

A further object of our invention consists in locking the coin receptacle in place by mechanism rendered accessible only when 100 the top of the magazine is removed.

A further object of our invention is to provide a vending machine with coin-controlled ejector mechanism which may at will be rendered operable without the deposition of a coin. In the specific construction shown for the sake of illustration in the accompanying drawings, the means for rendering the machine operable without the deposition of a coin is key-controlled, but it is obvious 105 110

that it may be controlled in other ways. The importance and advantages residing in this feature of our invention will be explained later on.

5 The above and other objects and advantages of our invention will become apparent from the detailed description of the accompanying drawings in which

10 Figure 1 is a sectional bottom plan view of a machine embodying our invention, the section being taken substantially on the broken line 1-1 of Fig. 2;

15 Fig. 2 is a vertical section on line 2-2 of Fig. 1, a portion of the magazine being broken away for economy of space on the drawing sheet, this figure showing the parts of the operating mechanism in normal or unoperated position;

20 Fig. 3 shows a section on line 3-3 of Fig. 2, the weight and cup being omitted for the sake of clearness; and

25 Fig. 4 is a vertical sectional view similar to Fig. 2, showing the parts of the operating mechanism in operated position.

30 The different parts which go to make up the operating mechanism of the machine are carried by the main casting indicated as a whole by A. When we refer to the part A as a casting, we do not mean that it is necessarily a piece of cast metal, but we use the term "casting" for convenience. While the part A is preferably made of cast metal, it may be formed of sheet metal or other material. The casting A comprises a body portion

35 1 which terminates at the front in a rounded platform 2. The body portion 1 is provided with upwardly-extending side flanges 3 and rear flange 4, between which the magazine 5 is rigidly secured by means

40 of rivets, screws or pins 6, one of which is shown in Fig. 2. The magazine 5 is preferably made of sheet metal and is of proper size to accommodate the vendible articles in a vertical stack. In Fig. 3 the flat cups or

45 envelopes are indicated in dotted outline at B. The front wall of the magazine is cut away at the bottom at 7 to form the delivery opening through which the cups are ejected. A suitable guard strip 8 is preferably pro-

50 vided in front of the delivery opening to prevent the ready insertion of instruments into the magazine, as well as to add to the finished appearance of the machine. In the particular construction shown in the draw-

55 ings, the strip 8 is substantially L-shaped in cross-section and is secured to the front wall of the magazine 5. The transverse ridge 9 of the casting A forms the bottom of the delivery-slot 7. The operating mechanism

60 of our new machine includes an ejector 10 arranged at the bottom of the magazine. This ejector lies flat upon the main casting and is adapted to slide back and forth between a pair of longitudinal guide flanges

65 11 formed on the body portion 1 of the

casting A, which really forms the bottom of the magazine. The rear end of the ejector 10 is provided with lateral wings or extensions 12 which ride over the guide flanges or rails 11 during the movement of the 70 ejector. The extensions 12 might thus be said to support the ejector on the rails 11. The ejector is at its rear end provided with an up-wardly-extending lug 13 by means of which the cups are ejected from the magazine, as will presently be explained. 75

To the underside of the main casting A is secured a frame indicated as a whole by C, by means of screws 14, or other suitable fastening devices. The frame C is provided 80 with a pair of rearwardly-extending portions 15 and 16, between which the coin-slide 17 is movably mounted. The frame C is sufficiently spaced from the main casting A, as indicated by 18, to provide free and 85 easy movement for the coin-slide 17. The coin-slide 17 is at its rear end rigidly secured to the ejector 10 by means of screws 19 or other suitable fastening devices. A guide block 20 is inserted between the 90 ejector and the coin-slide to guide the movement of the parts, the guide-block working in the longitudinal slot 21 formed in the bottom 1 of the magazine. The coin-slide 17 is on its underside provided with a pair of 95 spaced lugs 22 which carry the pin 23. To this pin is connected the forward end of the link 24 which is at the rear pivotally connected to the upper end of the arm 25 by means of a pin 26. The lower end of the 100 arm 25 is pivotally connected with the lower end of the bracket 27 by means of a pin or bolt 28. The bracket 27 depends from the under face of the main casting and is rigidly secured thereto in any suitable way. A push 105 rod 29 is at its rear end pivotally connected with the arm 25 at a point 30 substantially midway of the latter. By means of this simple connection between the coin-slide and the push rod the movement of the latter is 110 multiplied. Assuming the point of connection 30 between the push rod 29 and the arm 25 to be midway between the points 26 and 28, the stroke or movement of the ejector 10 is double that of the push rod 29. The 115 push rod need therefore extend only a short distance outside of the casing. In the construction shown in the drawing, the push rod 29 does not project beyond the rounded shelf 2 of the main casting. This prevents 120 the projecting portion of the push rod from becoming an obstruction or unsightly protrusion. The forward end of the push rod 29 is supported in the bracket 31 which projects downwardly from the frame C. The 125 bracket 31 is provided with an opening for receiving the push rod.

The extension 15 of the frame C is provided with a downwardly projecting bearing lug 32 which supports one end of the 130

shaft 33. The other end of this shaft is non-rotatably supported in the downwardly extending flange 34 provided on the extension 16 of the frame C. The shaft 33 is provided with a flattened portion 35 which works in a vertical slot (not shown) in the bearing flange 34. The object of this connection between the shaft 33 and the bearing flange 34 is to hold the shaft against 5 rotation and at the same time permit that end of the shaft to move vertically for a purpose to be presently explained. On the shaft 33 is rotatably mounted a sleeve 36 which carries at its outer end a sprocket 10 wheel 37 and at its inner end the coin-testing arm 38. The free or outer end of the arm 38 is so shaped as to form points 39 and 40 which are adapted to engage the deposited coin and test the same. This coin-testing 15 device does not in and of itself form a part of our present invention, it being the subject matter of Patent No. 625,123, granted May 16, 1899 to J. G. W. Romans and A. D. Grover as their joint invention. 20 As we have shown the machine in the accompanying drawings equipped with this Romans and Grover coin-testing device, we will describe the same for the sake of giving a complete description of what the drawings show. The sprocket wheel 37 is arranged to engage with the teeth 41 formed at one edge of the coin-slide 17, as best shown in Fig. 1. Whenever, therefore, the coin-slide is operated, the sleeve 36 is rotated together with the coin-testing arm 38. 25 A locking dog 42 is at 43 pivoted to the flange 34. The rear end of the locking dog 42 is provided with a hooked portion 44 which normally lies in the path of movement of the lug 45 extending laterally from the coin-slide 17. A suitably-arranged spring holds the locking dog 42 in the path of the lug 45. As shown in Fig. 1, the lug 45 is normally at some distance in front of the hooked portion 44 of the locking dog, so that the coin-slide is normally free to move inwardly until the lateral lug 45 engages the locking dog. Although the ejector 10 is always operated during the free movement of 30 the coin-slide, as just described, this movement of the ejector is what may properly be termed an inoperative or ineffective movement, because the ejector is not moved back sufficiently to cause the upright lug 13 to engage the underedge of the lowermost cup. Whenever, therefore, we have occasion in this specification to speak of the operation of the ejector, we do not refer to the ineffective movement which may be imparted to it by the normally free movement of the coin-slide. The purpose of this normally free movement of the parts is to give 35 the coin-testing device a chance to test the deposited coin. Although the operation of this device is fully described in the Romans and Grover patent above mentioned, the same may here be briefly described as follows: In the normal position of the different parts which go to make up the operating mechanism of our machine, the coin-slot 46 provided at the forward end of the coin-slide 17 is in alignment with the entrance-slot 47 in the rounded shelf 2 of the main casting A. Normally, the coin-testing arm 38 occupies substantially the position shown in Fig. 2. The deposited coin, substantially filling the slot 46, rests on the forward extension 48 of the frame C. As the rod 29 is then pushed inwardly, the coin is carried along by the slide 17. At the same time the testing arm 38 is rocked upwardly and the movement of the parts is so timed that the point 39 of the coin-testing arm bears against the inner shoulder of the raised edge of the coin. This temporary pivotal connection between the coin and the arm 38 forces the shaft 33 downwardly. As the downwardly-moving end of the shaft 33 bears against the locking dog 42, as clearly shown in Figs. 2 and 4, the hooked end 44 of the locking dog 42 is forced downwardly out of the path of movement of the lateral lug 45 provided on the coin-slide 17. As the rod 29 is pushed in farther, the point 40 of the coin-testing arm 38 bears against the undersurface of the coin after the point 39 has passed out of engagement therewith. This holds the locking dog 42 in depressed or releasing position until the lateral shoulder 49 on the coin-slide 17 has passed the free end of the locking dog. Should the deposited check be a washer, the point 40 of the coin-testing arm would enter into the opening of the washer after the point 39 had passed out of engagement with the edge of the washer, whereby the locking dog 42 would rise into locking position to engage with the shoulder 49. This would lock the coin-slide against further movement. It will of course be understood that we have here shown and described the coin-testing device of the Romans and Grover patent merely for the sake of illustration, and that so far as the various features of our invention are concerned, any suitable coin-testing device may be employed—provided of course that it does not interfere with the proper operation of the other parts of the machine. 45 We will now describe the ejection of the articles by the ejector 10. As previously stated, we will assume that the articles to be vended are flat cups designated B. These cups have the general shape of an envelop open at one end. At this open end or mouth the free edge 50 of the top side extends beyond the free edge 51 of the underside. In other words, these cups have the general shape of an envelop with extended flap—except that in the ordinary envelop used for mailing purposes, the flap extends from one 50

of the longer edges of the front face, while in the envelop shown in the drawings the flap extends from a short edge of the front face. It is obvious that the particular shape of the envelops is immaterial as long as the free end of one face extends beyond the free end of the other face at the opening or mouth of the envelop. These envelops or flat cups are placed in the magazine of the machine with the mouth downward—that is to say, the side which terminates at the edge 51 is the underside. The shape of the magazine 5 is such that the envelops are held in a vertical stack without danger of disarrangement due to jolting or otherwise. In order to prevent the fraudulent extraction of cups from the machine by the insertion of a sharp instrument, we have invented means by which the stack of cups is normally held in such a position that the lowermost cup is above the delivery-slot and therefore beyond reach of any instrument which may be inserted into the machine through the delivery-opening. At the same time we have made provision for the automatic adjustment of said means during the operation of the ejector mechanism to insure the delivery of the articles when the machine is operated after the deposition of a proper coin. This feature of our invention may be carried out mechanically in different ways, but we have in the drawings shown a specific embodiment thereof which we prefer on account of its simplicity and effectiveness of operation. In the specific construction shown in the drawings, the adjustable support for the stack of cups consists of a piece of U-shaped wire having legs or shanks 52 and a transverse connecting portion 53 at the forward end. The free ends of the shank members 52 pass through openings 54 in the main casting A and terminate in extensions 55 at the underside of said casting. In this way the rear end of the U-shaped support is pivotally connected with the main casting. As best seen from Fig. 3, the ejector 10 works between the shank members 52 of the adjustable support. A transverse wire 56 carried by the forward end of the ejector normally holds the forward end of the support above the delivery-opening 7, as clearly shown in Fig. 2. For the sake of clearness only one cup has been shown in Figs. 2 and 4, but it will be readily understood that any number of cups may be piled on top of each other. Disregarding for the moment the weight W which rests loosely on the stack of articles and to which specific reference will presently be made, it will be seen from Fig. 2 that normally the lowermost article (which is the article in position to be ejected) is at its forward end supported on the forward end of the U-shaped wire support. The latter is in turn held elevated at its forward end by the cross wire

56 on the ejector 10. In this position of the parts, the forward end of the lowermost cup is above the delivery-slot 7 and is utterly beyond reach of any instrument which may be inserted into the machine for the extraction of the cup. The shank members 52 are provided with upwardly displaced portions 57. As the ejector travels inwardly from its normal position, the cross wire 56 will come opposite the displaced portions 57 and enter the recesses formed by these portions. As soon as the cross wire 56 enters these recesses the forward end of the U-shaped support drops on to the plate 1 of the main casting behind the transverse ridge 80 9, as clearly shown in Fig. 4. This brings the forward end of the lowermost cup into alignment with the delivery-slot 7. When the ejector 10 has reached the limit of its rearward movement, the upstanding lug 13 85 at the rear end thereof has passed beyond the free edge 51 of the underside of the cup. Normally, the mouth of the cup is closed, as shown in Fig. 2. However, as soon as the lug 13 has passed beyond the edge 51, the 90 flap portion of the upper side of the cup is forced upwardly, thus causing the cup to gap. This allows the lug 13 to secure a firm engagement with the cup at the under-edge 51 as the ejector moves forwardly under 95 the action of the restoring spring 58. Considering Fig. 4, it will be seen that as the ejector moves forwardly—that is to say to the left (as viewed in this figure)—the lug 13 engages the underedge 51 at the center 100 thereof and carries the cup forwardly through the delivery-opening 7. As soon as the cross wire 56 at the front end of the ejector 10 has passed out of engagement with the displaced portions 57, the forward end 105 of the adjustable support for the articles is raised back into the position shown in Fig. 2. The ejector during its return movement causes enough of the cup to protrude through the delivery-slot that the protruding portion 110 may easily be grasped by the fingers and the cup be thus extracted from the machine. The fact that the adjustable support for the articles is moved upwardly into normal position, as the ejector reaches the end of its 115 ejecting movement, does not interfere with the ready extraction of the cup by hand, because these cups are sufficiently flexible to permit their extraction without mutilation. Furthermore, it should be noted in this connection that the engagement between the ejector and the cup to be ejected is not only positive, as distinguished from a mere frictional engagement, but it prevents injury 120 to the cup by the engaging portion of the 125 ejector. This entirely obviates the objections inherent in those ejector devices which engage the articles by mere frictional contact, whereby delivery is rendered uncertain and the articles are frequently mutilated by 130

the engaging portion of the delivery or ejecting mechanism.

It will be seen from the above that we have provided extremely simple and efficient means for preventing the fraudulent extraction of the articles from the machine. The basic idea of adjustable means for normally holding the forward end of the article next to be delivered out of alignment with the delivery-opening of the machine, and causing automatic adjustment of said means to bring the forward end of the article engaged by the ejector mechanism into alignment with the delivery-opening, may be mechanically embodied in different ways from that shown in the drawings. These embodiments would still fall within the scope of our invention as defined in certain of the appended claims.

In order to insure the alignment of the lowermost article at its forward end with the delivery-opening 7 when the adjustable supporting device is in lowered position, we have provided a weight W adapted to rest loosely on the stack of articles and so constructed as to exert a downward pressure on the forward end of the articles. Referring to Figs. 2 and 4, it will be observed that the weight W is at its forward end provided with a downwardly-extending transverse projection 59. In this way a downward pressure is continually exerted on the forward end of the articles, so that even the last of the articles is held in proper position for delivery, as may be seen in Fig. 4. Toward the rear, the weight W is provided with a downwardly-extending transverse projection 60, which is so arranged as to bear down upon the cups at a point a little to the front of the underedge 51. This insures the separation of the flap portion of the upper side from the underside, as is clear from Fig. 4, and allows the engaging lug 13 to secure a positive contact against the underedge 51 of the cup. The two transverse projections 59 and 60 form a recess 61 to accommodate the slightly upward bulge of the cups due to the raised portions 57 of the adjustable support. The rear projection 60 on the weight W performs another important function and that is, the positive locking of the ejector 10 against full rearward movement when the supply of cups in the magazine is exhausted. It will be readily understood from Figs. 2 and 4 that when the ejector is pushed inwardly after the deposition of a proper coin when the magazine is empty, the upstanding lug 13 will abut against the front shoulder 62 of the projection 60. This arrests further operation of the machine, and upon release of the push rod 29 the coin in the slot 46 of the coin-slide 17 is brought back into alignment with the entrance opening 47 through which it may be taken out by the patron. The cut-

away portion 63 on the forward extension 48 of the frame C permits a suitable instrument (such as a knife blade or point of a pencil) to be thrust upwardly by the patron against the underside of the coin, whereby the forward end of the latter may be raised out of the opening 47 to be grasped by the fingers. The patron is thus insured of the return of his coin, should he have attempted to operate the machine when the magazine was empty.

In the operation of the machine upon the deposition of a proper coin, the latter falls out of the coin-slot 46 after it has been tested by the arm 38. The casing 64, suspended from the main casting A, performs the double function of coin box and housing for those parts of the mechanism which project below the main casting. The coins drop from the slot 46 into the casing 64 which is removably locked in position. For this purpose the downwardly-extending flange 65 at the rear of the main casting A is provided with a pair of inwardly-extending pins 66 which are adapted to enter correspondingly-arranged openings in the rear wall of the coin box or casing 64. At the front the coin box is provided with an inwardly-extending pin 67 adapted to pass through a correspondingly-arranged opening 68 in the depending bracket arm 31 of the frame C. The push rod 29 passes through a correspondingly-arranged opening in the front wall of the coin box 64. It will thus be clear that the casing or coin box 64 is suspended from the main casting by means of the pins 66 and 67. In the absence of any locking arrangement, the box can be removed by simply sliding it forward a little until it is clear of the pins 66 and the opening 68, whereupon the rear end of the box will drop downwardly below the bracket 27 and the box be suspended at its forward end from the push rod 29. By a little manipulation the box may then be slid off the projecting portion of the push rod.

In order to prevent removal of the coin box by unauthorized persons, we have provided a locking device for the box, so arranged and constructed as to be accessible only when the top or cover of the magazine is removed. This top or cover is in turn locked in place by means of a lock to which only the authorized person has the key. Referring to Figs. 2 and 4, it will be seen that a vertical rod 69 is supported in the magazine 5 near one of the rear corners thereof by means of a suitable bracket 70 secured to the inside of the magazine. The horizontal arm of the bracket has an opening through which the rod passes. The lateral finger-piece 71 of the locking rod 69 rests upon the bracket, so that the rod normally hangs in locking position, with the lower

115

120

125

130

end 72 projecting through an opening in the bottom of the magazine. The lower end 72 of the locking rod 69 projects into the coin box in close proximity to the rear wall thereof, and thereby locks the box against sufficient movement to clear the pins 66. The top or cover 73 of the magazine 5 is securely locked in place in any suitable way. In the drawings we have shown the cover 10 73 provided with a downwardly-extending flange 74 on all four sides, so that the cover may snugly fit over the upper end of the magazine. The rear portion of the flange 74 is provided with one or more pins 75 which pass through correspondingly arranged openings 76 in the rear wall of the magazine. Near the front end the cover is provided with a suitable lock indicated as a whole by L and adapted to be operated 20 by a key. The locking bolt 77 of the lock L is adapted to engage beneath the rearwardly-extending lip 78 on the front wall of the magazine. To remove the coin box 64, the top 73 must first be unlocked and re- 25 moved, whereupon the locking rod 69 may be lifted until the fixed collar 79 thereon abuts against the bracket 70. This raising of the locking rod 69 moves the lower end 72 out of locking position, so that the coin 30 box is now released and may be taken off the machine entirely or let down sufficiently at the rear end for the removal of the coins.

As we have explained above in detail, the 35 ejector of our machine cannot be operated unless a proper coin is first deposited. Conditions, however, might arise in which it would be desirable or even necessary to operate the machine without the deposition of a coin. For instance, if our machine is used 40 on the cars of a railway train which runs in its course through several States, in all of which the use of public drinking cups on trains is prohibited by legislation, and in some of which States the railroad company 45 is compelled to furnish patrons free of charge with individual drinking cups, our machine can be used to meet both conditions. That is to say, when the train passes through those States in which the company is not 50 obliged to furnish patrons free with individual drinking cups, our machine may be so set as to operate only upon the deposition of a coin. However, as soon as the train enters a State in which the law requires the 55 railroad company to provide the travelers with individual cups free of charge, our machine is capable of such adjustment that it may be operated without the requirement of a coin. Considered in its broad aspect, 60 this feature of our invention by which the machine may be made to operate at will either with or without the deposition of a coin, may be carried out in a number of ways, one of which we have for the sake of 65 illustration shown in the accompanying

drawings. A bell-crank 80 is at 81 pivoted to the extension 82 on the flange 34 of the frame C. The upwardly-extending rear arm of the bell-crank is provided with a lateral lug 83 which extends over the locking dog 42 near the free end thereof, as best shown in Figs. 1 and 4. The free end of the forwardly-extending arm of the bell-crank 80 is arranged over the bolt 84 of a suitable lock 85 secured to the inside of the coin box 75 64. When the bolt 84 of the lock 85 is in withdrawn position, the bell-crank 80 does not in the least interfere with the operation of the machine upon the deposition of a coin, as previously described in detail. The 80 lug 83 of the bell-crank simply rests by gravity on the locking dog 42. When it is desired to operate the machine without the deposition of a coin, the bolt 84 is thrust upwardly by means of a key inserted in 85 the lock 85. This upward movement of the bolt 84 throws the forward end of the bell-crank 80 upwardly and the rear end downwardly. As the lateral lug 83 lies over the locking dog 42, this rocking of the bell- 90 crank by the bolt 84 throws the free end of the locking dog downwardly out of the path of movement of the lateral lug 45 and shoulder 49 on the coin-slide 17. The locking dog 42 being thus rocked into inoperative position, the ejector 10 is free to operate to the limit of its inward movement to eject the articles from the magazine, in exactly the same way as when the machine is operable only upon the deposition of a coin. To adjust the machine for operation with a coin only, it is but necessary to turn the key in the lock 85 to withdraw the bolt 84. If our machine be used on a train, the key to the lock 85 would be in the custody of the conductor or other official. It should be noted that the lock 85 is for the sole purpose of setting the machine to operate with or without a coin, and has nothing to do with the locking or unlocking of the coin box itself. 105 It will be understood that the means for adjusting the mechanism of the machine to permit its operation without or only upon the deposition of a coin, need not be necessarily key-controlled, although the use of a key makes the adjustment an extremely simple matter.

While we have herein shown and described a specific form of machine embodying the various features of novelty which characterize our invention, we would have it understood that we do not intend to be limited to the details of such specific form, as it is obvious that changes and modifications may be resorted to without departing from 120 the scope of our invention as defined in the appended claims. Furthermore, it is clear that some of the features of our invention may be embodied in a machine without the presence of other features. 130

Having thus described our invention, what we claim as new and desire to secure by Letters Patent of the United States, is:

1. In a vending machine having a magazine for containing a vertical stack of flat, flexible articles in which the upper side extends beyond the free edge of the underside to form a mouth or opening at the said underside, the combination with a slidably ejector adapted to engage the lowermost article at said free edge to eject the same from the magazine, said ejector normally engaging said upper extension on the article and pressing upwardly against the same, of a weight adapted to rest on the stack of articles and provided on its underside with a rib or projection arranged to bear down upon the articles at a point near the mouth, whereby the mouth of the article is automatically caused to gap under the downward pressure of said rib and the upward pressure of said ejector.

2. In a vending machine having a magazine for containing a vertical stack of flat, flexible articles in which the upperside extends beyond the free edge of the underside to form a mouth or opening at said underside, the combination with a slideable ejector having at its rear end an upstanding lug adapted to engage the lowermost article at said free edge to eject the same from the magazine, said lug normally engaging said upper extension on the article pressing upwardly against the same, of a weight adapted to rest on the stack of articles and provided on its underside with a rib or projection arranged to bear down upon the articles at a point near the mouth, whereby the mouth of the article is automatically caused to gap under the downward pressure of said rib and the upward pressure of said lug.

3. In a vending machine having a magazine for containing a vertical stack of flat, flexible articles in which the upperside extends beyond the free edge of the underside, to form a mouth or opening at said underside, the combination with a slidable ejector having means to engage the lowermost article at said free edge to eject the same from the magazine, said engaging means exerting upward pressure against said free edge of the article, of means adapted to exert downward pressure on the articles at a point near the mouth, whereby the mouth of the article is automatically caused to gap under said upward and downward pressure.

4. In a vending machine, a magazine for containing the vendable articles in a vertical stack, said magazine being at its lower end provided with a delivery-opening, adjustable means at the bottom of said magazine for normally supporting the forward end of the lowermost article above said delivery-opening, ejector mechanism operable to eject the articles through said delivery-opening.

means whereby the operation of said ejector mechanism causes automatic lowering of said supporting means to bring the forward end of the lowermost article into alignment with said delivery-opening, a weight adapted to rest loosely on the stack of vendable articles, and a downwardly-extending projection at the forward end of said weight to exert a downward pressure on the forward end of the articles and thus insure the alignment of the lowermost article at its forward end with said delivery-opening, when said adjustable supporting means is in lowered position. 70 75

5. In a vending machine, a casing for containing the vendable articles in a vertical stack, said magazine being at its lower end provided with a delivery-opening, adjustable means at the bottom of said magazine for normally supporting the forward end of the lowermost article above said delivery-opening, ejector mechanism operable to eject the articles through said delivery-opening, means carried by said ejector mechanism to hold said adjustable supporting means in its normal position, said means carried by the ejector mechanism causing said supporting means to drop automatically during the operation of said mechanism sufficiently to bring the forward end of the lowermost article into alignment with said delivery-opening, a weight adapted to rest loosely on the stack of vendable articles, and a downwardly-extending projection at the forward end of said weight to exert a downward pressure on the forward end of the articles and thus insure the alignment of the lowermost article at its forward end with said delivery-opening, when said adjustable supporting means is in lowered position. 105

6. In a vending machine, a magazine for containing the vendable articles in a vertical stack, said magazine being at its lower end provided with a delivery-opening, adjustable means at the bottom of said magazine for normally supporting the forward end of the lowermost article above said delivery-opening, a slidable ejector having means at the rear end for engaging the lowermost article to eject the same through said delivery-opening, means at the forward end of said ejector to hold said adjustable supporting means in its normal position when the ejector is in unoperated position, said holding means on the ejector automatically releasing said adjustable supporting means and allowing the same to drop when the ejector is operated, whereby the forward end of the lowermost article is brought into alinement with the delivery-opening, and a weight adapted to rest loosely on the stack of articles and provided with two downwardly-extending projections, one of these projections being at the front to exert a downward pressure 130

on the forward end of the articles and thus insure the alinement of the lowermost article at its forward end with said delivery-opening when said adjustable supporting means is in lowered position, the other projection being arranged toward the rear to engage the ejector and prevent operation thereof when the magazine is empty.

7. In a vending machine, a magazine for containing the vendable articles in a vertical stack, said magazine being at its lower end provided with a delivery-opening, a slidable ejector at the bottom of said magazine for ejecting the articles through said delivery-opening, a U-shaped member pivoted at the free end of its shanks at the bottom of said magazine, the transverse forward end of said member being arranged in proximity to said delivery-opening to support the forward end of said stack of articles, the shanks of said member extending on either side of said ejector and having intermediate offset portions which form recesses, and means carried by the ejector for engaging said shanks at one side of said offset portions to maintain the forward end of the lowermost article above said delivery-opening when the ejector is unoperated, said means on the ejector engaging in said recesses when the ejector is operated, whereby said member rocks down to bring the forward end of the lowermost article into alinement with the delivery-opening.

8. In a vending machine, a magazine for containing the vendable articles in a vertical stack, said magazine being at its lower end provided with a delivery-opening, a slidable ejector arranged at the bottom of said magazine and provided at its rear end with a lug for engaging the lowermost article and ejecting the same through said delivery-opening, a U-shaped member formed of a piece of wire pivoted at the free end of its shanks at the bottom of said magazine, the transverse forward end of said member being arranged in proximity to said delivery-opening to support the forward end of said stack of articles, the shanks of said member extending on either side of said ejector and having intermediate offset portions which have recesses, and a transverse rod carried by the ejector for engaging said shanks at one side of said offset portions to maintain the forward end of the lowermost article above said delivery-opening when the ejector is unoperated, the opposite ends of said transverse rod engaging in said recesses when the ejector is operated, whereby said member rocks down to bring the forward end of the lowermost article into alinement with the delivery-opening.

9. In a vending machine, a magazine for containing the vendable articles in a vertical stack, said magazine being at its lower end provided with a delivery-opening, a

slidable ejector arranged at the bottom of said magazine and provided at its rear end with a lug for engaging the lowermost article and ejecting the same through said delivery-opening, a U-shaped member formed of a piece of wire pivoted at the free end of its shanks at the bottom of said magazine, the transverse forward end of said member being arranged in proximity to said delivery-opening to support the forward end of said stack of articles, the shanks of said member extending on either side of said ejector and having intermediate offset portions which have recesses, a transverse rod carried by the ejector for engaging said shanks at one side of said offset portions to maintain the forward end of the lowermost article above said delivery-opening when the ejector is unoperated, the opposite ends of said transverse rod engaging in said recesses when the ejector is operated, whereby said member rocks down to bring the forward end of the lowermost article into alinement with the delivery-opening, and a weight adapted to rest loosely on the stack of articles and provided with two downwardly-extending projections, one of these projections being at the front to exert a downward pressure on the forward end of the articles and thus insure the alinement of the lowermost article at its forward end with said delivery-opening when said adjustable supporting means is in lowered position, the other projection being arranged toward the rear to engage the lug on the ejector and prevent operation of the ejector when the magazine is empty.

10. In a vending machine having a magazine for containing a vertical stack of flat flexible articles in which the upper side extends beyond the free edge of the underside to form a mouth or opening at said underside, the combination with a slidable ejector adapted to engage the lowermost article at said free edge to eject the same from the magazine, said ejector normally engaging said upper extension on the article and exerting an upward pressure against the same, of a weight provided with two downwardly extending projections, one of which bears down upon the article at the forward or delivery end thereof to insure its alinement with the delivery-opening of the magazine, the other of said projections bearing down upon the article near said free edge on the under side to cause the mouth of the article to gap automatically under the downward pressure of said last named projection and the upward pressure of said ejector.

11. In a vending machine having a magazine for containing a vertical stack of flat flexible articles in which the upper side extends beyond the free edge of the underside to form a mouth or opening at said underside, the combination with a slidable ejector

having at its rear end an upstanding lug adapted to engage the lowermost article at said free edge to eject the same from the magazine, said lug normally engaging said upper extension on the article and pressing upwardly against the same, of a weight provided with two downwardly extending projections, one of which bears down upon the article at the forward or delivery end thereof, to insure its alinement with the delivery opening of the magazine, the other of said projections bearing down upon the article at a point near the mouth thereof, to cause said mouth to gap automatically under the downward pressure of said last named projection and the upward pressure of said lug.

12. In a vending machine provided with a magazine for containing thin, flexible articles in a vertical stack, a weight adapted to rest loosely upon the stack of articles, a downwardly extending transverse projection at the forward end of said weight, and a downwardly extending projection at the rear end of said weight, whereby pressure is brought to bear upon the stack on two transverse lines to permit flexing of the articles.

13. In a vending machine, a main casting, a closed outer casing secured to the upper portion of said casting and forming the magazine in which the vendable articles are contained, the upper side of said casting constituting the bottom of said magazine, a delivery-opening formed in the front wall of said outer casing just above said casting, an ejector slideable over the upper side of said casting to eject the articles through said opening, a slideable hand-operated member supported beneath said casting, an operative connection between said ejector and said member, and a second outer casing removably supported by and beneath said casting and having an opening in the front wall

through which said hand-operated member projects.

14. In a vending machine, a main casting, 45 a closed outer casing secured to the upper portion of said casting and forming the magazine in which the vendable articles are contained, a delivery-opening formed in the front wall of said outer casing just above 50 said casting, ejector mechanism carried by said casting to eject the articles through said delivery-opening, and a second closed outer casing removably supported from said casting beneath the same.

15. In a vending machine provided with a magazine for containing the vendable articles, a U-shaped wire lying flat on the bottom of the magazine for normally supporting the articles above the delivery-opening, a 60 slideable ejector provided at its forward end with a transverse rod or wire adapted to co-operate with said U-shaped wire to permit the delivery of the articles when the ejector is operated.

16. In a vending machine provided with a magazine for containing the vendable articles, in combination a flat ejector adapted to slide over the bottom of said magazine, said bottom having a slot, formed therein, a slide 70 movable beneath the bottom of the magazine, said ejector and said slide being substantially parallel to each other, means for securing the said ejector to said slide, said means including a block arranged to move 75 in said slot, and means for operating said slide.

In witness whereof, we hereunto subscribe our names, this 12th day of December, 1911.

ALBERT D. GROVER.
EARL E. BARBER.

Witnesses for both:

ELIZABETH T. RALEIGH,
EDWARD J. RALEIGH.
